US0D1008863S

(12) **United States Design Patent** (10) **Patent No.:** **US D1,008,863 S**
(45) **Date of Patent:** **** Dec. 26, 2023**

(54) **JEWELRY COMPONENT**

(71) Applicant: **Venus by Maria Tash, Inc.**, New York, NY (US)

D136,958 S 10/1943 Rubel
D137,112 S 10/1943 Rubel
D139,254 S 8/1944 Philippe
(Continued)

(72) Inventor: **Maria Tashjian**, New York, NY (US)

FOREIGN PATENT DOCUMENTS

(73) Assignee: **Venus by Maria Tash, Inc.**, New York, NY (US)

CN 305577860 * 1/2020
FR 2886110 12/2006
KR 300967884.0000 * 12/2017

(**) Term: **15 Years**

(21) Appl. No.: **29/749,236**

(22) Filed: **Sep. 3, 2020**

(51) LOC (14) Cl. **11-01**

(52) U.S. Cl.

USPC **D11/86**

FIG. 1 is a frontal view of a jewelry component;

FIG. 2 is a back view thereof;

FIG. 3 is a top view thereof;

FIG. 4 is a bottom view thereof;

FIG. 5 is a left view thereof;

FIG. 6 is a right view thereof; and,

FIG. 7 is a perspective view thereof.

The broken line boundary in FIG. 2 forms no part of the claimed design. The portions of the jewelry component shown in the broken line form no part of the claimed design.

1 Claim, 7 Drawing Sheets
